UNITED STATES PATENT OFFICE.

WILLIAM A. BJORKLUND AND AUGUST HOLMQUIST, OF HOOPESTON, ILLINOIS,
ASSIGNORS TO SPRAGUE CANNING MACHINERY COMPANY, OF CHICAGO, ILLINOIS, A CORPORATION OF ILLINOIS.

FILLING MACHINE.

Application filed June 1, 1920. Serial No. 385,458.

To all whom it may concern:

Be it known that we, WILLIAM A. BJORKLUND and AUGUST HOLMQUIST, citizens of the United States, residing at Hoopeston, 5 in the county of Vermilion and State of Illinois, respectively, have invented certain new and useful Improvements in Filling Machines, of which the following is a full, clear, concise, and exact description, reference being had to the accompanying drawings, forming a part of this specification.

Our invention relates to filling machines and more specifically to hand-pack filling machines, one type of hand-pack filling machine being shown in the patent to Lowe, 15 No. 1,200,277, dated October 3, 1916.

One of the objects of our invention is to provide a hand-pack filler, which will be compact in construction so as not to take 20 up much room in a canning plant and which will be of large capacity for its size and which will be durable and efficient in use, and cheap to manufacture.

Further objects will appear from the detailed description to follow and from the appended claims.

In the drawings in which one embodiment of our invention is shown—

Fig. 1 is a side elevation of a filling machine having a portion of the briner cut away to show the interior thereof;

Fig. 2 is a top plan view of Fig. 1;

Fig. 3 is a sectional plan view substantially on line 3—3 of Fig. 4;

Fig. 4 is a vertical sectional view taken substantially on line 4—4 of Fig. 3;

Fig. 5 is an enlarged vertical sectional view taken on line 5—5 of Fig. 1;

Fig. 6 is a detail view of one of the can sweeps and a mouthpiece or funnel member supported on the same spindle; and

Fig. 7 is a top plan view of Fig. 6.

In order to give a general idea of the construction as shown in the drawings, it is here stated that it comprises an elongated stationary central holder or trough, in which the fruit to be filled into cans, such as tomatoes and the like, is placed, an endless chain traveling adjacent the periphery of said trough or holder, in a horizontal plane, a series of mouthpieces or funnel members secured to said chain, and a series of can sweeps also secured to said chain for carrying the cans to be filled along with

and underneath said mouthpieces or funnels. 55

Suitable means are provided for feeding the cans to the sweeps of the endless conveyor, and for causing them to be discharged from said sweeps, and if desired, a brining attachment may be provided for supplying measured quantities of liquid or brine to the cans as they are carried along.

To give a more detailed description of our construction, the construction shown comprises an elongated, stationary central 65 trough or holder 10, which trough has a peripheral edge 11. Said trough is suitably supported upon a base or arm comprising side members 12 supported upon the leg members 13, said legs being connected 70 by cross members or brackets 14 and 15. Positioned upon the side members 12 are can tracks 16 to receive the empty cans from the feed disc 17 from whence they are carried along said track and filled, the filled cans 75 being then deposited on a discharge disc 18. Can sweeps 19 secured to an endless traveling chain, as hereinafter described, are positioned to travel above said tracks so as to carry the cans from the feed disc 17 80 along the tracks on to the discharge disc 18. These can sweeps 19 have integrally formed therewith an eye portion 20, and a lug 21, said eye portion having a spindle 22 secured therein, upon which spindle is supported a funnel-shaped member or mouthpiece 23, which mouthpiece registers above the can when carried along the track by said can sweep and which facilitates the filling of the cans by the operator. Each of the 85 mouthpieces or funnel members 23 has an opening 24 therein from which opening extends a flange portion 25 which facilitates the positioning of the funnel member on the can. 95

The can sweep 19, spindle member 22, and the funnel member 23 are carried as a unit by the lug 21 on the can sweep 19, being secured to an endless traveling chain 26 which extends around sprocket wheels 27 100 and 27^a, said sprocket wheel 27^a being the driving sprocket on the briner end of the machine. This sprocket wheel 27^a is secured at 28, as shown in Fig. 5, to a sleeve 29 which is rotatably mounted upon the stationary shaft or post 30, which shaft is secured at 31 to the bracket 14. Said sleeve 29, as shown at 32, has also secured thereto 105

a bevel gear 33, which is driven by a bevel gear 34 from the shaft 35, which is, in turn, driven from any suitable source of power.

Deflector arms 36 and 37 are secured at 5 38 and 39 respectively to the table member 12. The purpose of the deflector arm 36 is to deflect the cans on to the track 16. The deflector arm 37, in turn, deflecting the 10 filled cans from the track 16 on to the discharge disc 18.

The briner 40 may be positioned on said machine at the driving end thereof, which briner comprises a central sleeve 41 secured at 42 to the sleeve 29, a central reservoir 43 secured to the sleeve 41, and a plurality of measuring chambers 44 located in said reservoir 43. Each of said measuring chambers has a passage 45 leading from said reservoir into said measuring chamber. Positioned directly below said measuring chambers are discharge openings 46 for the passage of the brine from the measuring chambers into the cans. Leading from the central reservoir 43 into the passages 45 are ports 47, the edges of these openings forming seats for valves 48, which valves are normally in closed position. Similarly, valve seats or ports 49 are positioned directly below the measuring chambers 44 which seats 49 have cooperating therewith the valves 50, which also normally close said ports 49. These valves are retained in their normal closed position by means of tension springs 51.

For controlling the action of the valves 48 and 50, the stationary shaft 30 which extends upwardly through the sleeve 29, out through the upper end of the briner 40, has secured thereto, a hub portion 52, which is secured at 53, as clearly shown in Fig. 5, and supports the semi-circular cams 54 and 55, respectively, which are formed integral therewith. As clearly shown in Figs. 1 and 2, the cam 54 is considerably smaller in diameter than the cam 55, the cam 54 being located to control the inner circle of valves 48 and the cam 55 being located to control the outer circle of valves 50. Inwardly radially projecting fingers 56 are secured to the stems of the valves 48 and are positioned so as to ride on the cam 54 to raise the valves at proper time for filling the chambers 44.

Similarly, the valve stems of the outer circle of valves 50 are provided with inwardly projecting fingers or followers 57, which are positioned so as to engage the cam 55, as these valves revolve together with the compartment 43.

For adjusting the capacity of the measuring chambers 44, they are provided with vertically-adjustable pistons or partitions 58, which frictionally engage the walls of the chambers, to determine the height to which the brine or liquid can rise in these chambers. In order that these pistons may

be readily adjusted vertically, and also in order to provide means for the escape of the air from the chambers when the brine is entering, sleeves 59 are provided which are secured to the pistons and surround the 70 valve stems. The bore of these sleeves is slightly larger than the diameter of the valve stems so that the air can pass up through these sleeves around the valve stems. These sleeves extend somewhat above 75 the upper edge of the reservoir 43, so that they are accessible to the operator for vertical adjustment to adjust the capacity of the measuring chambers.

The use and operation of the device is 80
as follows: The fruit to be filled in the
cans, which may be tomatoes or the like, is
dumped into the elongated trough or holder
10. The operators stand alongside this
trough or holder in position to draw the 85
fruit over the edge of the holder and cause
it to pass through the mouthpieces 23 into
the cans underneath. If the briner is not
to be used, operators may stand on both
sides of the machine. If the fruit is of 90
such nature that it requires the use of the
briner the operators will stand on only one
side of the table, that is, the side along
which the cans pass before they come under
the briner. 95

The machine is put in operation to cause the mouthpieces 23 and the can sweeps 19 to travel around the stationary trough or holder 10, and to cause the briner 40 to revolve, the endless traveling chain 26 to 100 which the can sweeps and mouthpieces are secured, being driven from the shaft 35 through the bevel gears 33 and 34, the sleeve 29 and the sprocket wheel 27^a.

The rotation of the sleeve 29 also causes 105 the briner 40 to revolve and with it the measuring chambers 44 and the controlling valves 48 and 50. As the can sweeps 19 and mouthpieces 23 travel along empty cans are fed in front of the can sweeps from the feed 110 discs 17 and are positioned under the mouthpieces 23, the openings of the cans registering with the annular flanges 25 of these mouthpieces.

The machine may be made long enough, 115
so that a considerable number of operators
can use the same machine. If there should
be, for instance, four operators employed in
filling the cans, each operator would fill
every fourth can, that is, the operator who
was standing nearest the feed disc 17 would
fill one can and then let three go by, and
fill the fifth one, the second operator would
fill the can immediately following the can
which had been already filled, and the third 125
operator would fill the can immediately
following the two filled cans, etc. It may
also be of interest to state that there may
be a further division of labor, that is, that
it may be the duty of some of the operators 130

to fill the cans approximately full, and the duty of others to top them off, that is, to add to the cans which have been approximately filled, to make them just right. That is, it may be the duty of one set of operators to fill the cans roughly, and the duty of another set of operators to finish them off nicely.

If the briner is to be used, the compartment 43 is kept supplied with brine or whatever liquid is to be used, and the cans as they travel around underneath the discharge openings 46 of the briner are supplied with a measured quantity of brine from the measuring chambers 44. The cams 54 and 55 are located so that the measuring chambers 44 will be discharging during that part of their travel in which cans are located underneath the discharge opening, and so that the measuring chambers 44 will be filling during that part of travel of the measuring chambers in which no cans are underneath the discharge openings 46. As shown in Fig. 2, the cam 55 will cause the valves 50 to be opened during the time in which the cans are traveling around the end of the machine, the valves 48, at the same time being closed, because they are not at that time under the control of the cam 54. It will also be seen that the cam 54 will cause the valves 48 to be opened during the time in which the fingers or followers 56 are in engagement with this cam and that the valves 50 will at the same time be closed, being not then under the control of the cam 55, and being closed by the tension spring 51. This alternate opening and closing of the valves 48 and 50 will cause the brine to enter the measuring chambers 44 during a part of the revolution of the reservoir 43 and will cause the measured quantities of brine or liquid in the chambers 44 to be discharged into the cans, as the cans travel around underneath the discharge openings 46.

As the brine rushes into the measuring chambers 44 through the passages 45, the air which is in the measuring chambers is permitted to escape up through the sleeve 59.

After the cans have been suitably filled, they are deflected onto the discharge disc 18 by means of the deflector 37.

The elongated formation of the filling machine permits a comparatively large number of operators to use the same machine, and this elongated formation also makes it so that a relatively small floor space is required for the installation and operation of the machine.

While only one embodiment of the invention is shown herein, it is to be understood that many modifications and variations thereof may be made without departing from the spirit and scope of the appended claims.

Having thus described our invention, what we claim as new and desire to secure by Letters Patent is:

1. A filling machine comprising an elongated fruit holder, the space above said holder being unobstructed so that the fruit is accessible to an operator adjacent the machine, means for moving a series of cans along said fruit holder, and for moving a series of mouth pieces along with the cans, whereby the operator can readily transfer the fruit from the holder into the cans. 70

2. A filling machine comprising a stationary elongated fruit holder, the space above said holder being unobstructed so that the fruit is accessible to an operator adjacent the machine, means for moving a series of cans along said fruit holder and for moving a series of mouth pieces along with the cans, whereby the operator can readily transfer 75 the fruit from the holder into the cans. 80

3. A filling machine comprising a stationary elongated fruit holder, said holder having a peripheral edge, the space above said edge being unobstructed so that the fruit is accessible to an operator adjacent the machine, so that the operator can remove the fruit from the holder adjacent the peripheral edge thereof, and means for moving a series of cans along said peripheral edge, 90 whereby the operator can readily transfer 95 the fruit from the holder to the cans.

4. A filling machine comprising a stationary fruit holder having a peripheral edge, the space above said edge being unobstructed 100 so that the fruit is accessible to an operator adjacent the machine and so that the operator can remove fruit from the holder adjacent the peripheral edge thereof, means for moving a series of cans along and adjacent 105 said peripheral edge, and for moving a series of mouth pieces along said peripheral edge along with the cans, whereby the operator can readily transfer the fruit from the holder into the cans. 110

5. A filling machine comprising a stationary elongated fruit holder, said holder having a peripheral edge, the space above said edge being unobstructed so that the fruit is accessible to an operator adjacent the machine, so that the operator can remove the fruit from the holder adjacent the peripheral edge thereof, and means for moving a series of cans along said peripheral edge, 115 whereby the operator can readily transfer the fruit from the holder to the cans, said can moving means comprising an endless conveyor. 120

6. A filling machine comprising a fruit holder having a peripheral edge, the space above said edge being unobstructed so that the fruit is accessible to an operator adjacent the machine, and so that the operator can remove fruit from the holder adjacent the peripheral edge thereof, means for moving 125 130

a series of cans along and adjacent said peripheral edge, and for moving a series of mouth pieces along said peripheral edge along with the cans, whereby the operator 5 can readily transfer the fruit from the holder into cans.

7. A filling machine comprising an elongated fruit holder, said fruit holder having a peripheral edge, the space above said edge 10 being unobstructed so that the fruit is accessible to an operator adjacent the machine, and so that the operator can remove fruit from the holder adjacent the peripheral edge thereof, and means for moving a series 15 of cans along and adjacent said peripheral edge whereby the operator can readily transfer the fruit from the holder to the cans, said means comprising an endless member, provided with means for engaging the cans 20 to move them along, and a series of mouthpieces secured to said endless member to travel along with and above the cans.

8. A filling machine comprising an elongated fruit holder, a pair of sprocket wheels, 25 one at each end of said holder, an endless chain traveling around said sprocket wheels, said chain being provided with means for engaging and moving a series of cans along and adjacent the peripheral edge of the 30 holder, the space above said edge being unobstructed so that the fruit is accessible to an operator adjacent the machine whereby the operator can readily transfer the fruit from the holder into the cans.

35 9. A filling machine comprising an elongated fruit holder, a pair of sprocket wheels, one at each end of said holder, an endless chain traveling around said sprocket wheels, said chain being provided with means for 40 engaging and moving a series of cans along and adjacent the peripheral edge of the holder, the space above said edge being unobstructed so that the fruit is accessible to an operator adjacent the machine, mouth- 45 pieces secured to said endless chain whereby the operator can readily transfer the fruit from the holder through the mouthpieces and into the cans.

50 10. A filling machine comprising a fruit holder, the space above said holder being unobstructed so that the fruit will be accessible to an operator adjacent the machine, a pair of rotatable members, one at each end of the machine, an endless member run-

ning over said rotatable members, said endless member being provided with means for moving a series of cans around said fruit holder, and means for supplying brine to said cans as they move around the rotatable members at the end of the machine. 55

60 11. A filling machine comprising an elongated fruit holder having a peripheral edge, the space above said edge being unobstructed so that the fruit will be accessible to an operator adjacent the machine, so that the operator can remove the fruit from the holder adjacent the peripheral edge thereof, a pair of rotatable members, one at each end of the machine, each rotating in a horizontal plane, an endless member running over 70 said rotatable members, said endless member being provided with means for moving a series of cans along and adjacent the peripheral edge of the holder, and means for supplying brine to said cans as they move 75 in a semi-circular path around the rotatable member at the end of the machine.

12. A filling machine comprising an elongated fruit holder having a peripheral edge, the space above said edge being unobstructed 80 so that the fruit will be accessible to an operator adjacent the machine, so that the operator can remove the fruit from the holder adjacent the peripheral edge thereof, a pair of rotatable members, one at each end of the 85 machine, each rotating in a horizontal plane, an endless member running over said rotatable members, said endless member being provided with means for moving a series of cans along and adjacent the peripheral edge 90 of the holder, mouthpieces secured to said endless member, and means for supplying brine to said cans through the mouthpieces as they move in a semi-circular path around the rotatable member at the end of the machine. 95

13. A filling machine comprising an elongated fruit holder, unitary means for each can movable around said fruit holder, and a chain and sprocket for moving said means, 100 said unitary means comprising a can sweep for directing the movement of each can around the fruit holder, and a funnel member for directing the fruit into each can.

In witness whereof, we have hereunto subscribed our names.

WILLIAM A. BJORKLUND.
AUGUST HOLMQUIST.
